Notice of Allowance dated May 19, 2020 issued in U.S. Appl. No. 29/690,020 (7 pages).

Primary Examiner — Dana Meyrow(74) *Attorney, Agent, or Firm* — Rothwell, Figg, Ernst & Manbeck, P.C.; Charles B. Cappellari, Esq.(57) **CLAIM**

The ornamental design for a bottle, as shown and described.

DESCRIPTION

FIG. 1 shows a top perspective view of the bottle.

FIG. 2 shows a front elevation view thereof.

FIG. 3 shows a back elevation view thereof.

FIG. 4 shows a left-side elevation view thereof.

FIG. 5 shows a right-side elevation view thereof.

FIG. 6 shows a top plan view thereof.

FIG. 7 shows a bottom plan view thereof; and,

FIG. 8 shows a bottom perspective view thereof.

The evenly-dashed broken lines in the drawings illustrate the portions of the bottle that form no part of the claimed design. The dot-dash broken lines in the drawings define the bounds of the claim and form no part thereof.

1 Claim, 8 Drawing Sheets(56)
